CLAIM

(52) **U.S. Cl.** USPC **D14/485**; D14/491

The ornamental design for a display panel or portion thereof with a graphical user interface, as shown and described.

(58) **Field of Classification Search**

DESCRIPTION

USPC D14/485-495
CPC G06F 3/048; G06F 3/0481; G06F 3/04812; G06F 3/04817; G06F 3/0482; G06F 3/0483; G06F 3/0484; G06F 3/04847; G06F 3/0485; G06F 3/04855; G06F 3/04886; G06Q 30/00; H03J 1/00; H03J 1/0008; H03J 1/0016; H03J 1/0025; H04N 5/00; H04N 5/08; H04N 5/14; H04N 5/222; H04N 5/225; H04N 5/232; H04N 5/445; H04N 5/44543; H04N 5/45; H04N 21/00; H04N 21/234; H04N 21/431; H04N 21/4312; H04N 21/4314; H04N 21/4316; H04N 21/4532; H04N 21/4622; H04N 21/47; H04N 21/478;

FIG. 1 is a front view of a display panel or portion thereof with a graphical user interface showing a first embodiment of our design; and,

FIG. 2 is a front view of a display panel or portion thereof with a graphical user interface showing a second embodiment thereof.

The outermost broken line rectangle illustrates a display panel or portion thereof and forms no part of the claimed design. The remaining broken lines, including all text, illustrate portions of the graphical user interface or a mixed reality environment, and form no part of the claimed design.
